UNITED STATES PATENT OFFICE.

SAMUEL E. WRIGHT, OF AUGUSTA, KANSAS.

TIME-CONTROLLED CIRCUIT-BREAKER.

1,297,529.

Specification of Letters Patent. Patented Mar. 18, 1919.

Application filed December 20, 1917. Serial No. 208,063.

To all whom it may concern:

Be it known that I, SAMUEL E. WRIGHT, a citizen of the United States, residing at Augusta, in the county of Butler, State of Kansas, have invented a new and useful Time-Controlled Circuit-Breaker; and I do hereby declare the following to be a full, clear, and exact description of the invention, such as will enable others skilled in the art 10 to which it appertains to make and use the same.

This invention relates to a time controlled circuit breaker, and one of the objects of the invention is the provision of a device of this 15 kind particularly adapted for breaking the circuit which controls the electric lights of a show window at a predetermined time.

A further object of the invention is the provision of a time controlled switch, comprising a knife switch, and a device connected to the knife blade switch, combination with a clock mechanism with means on the alarm key thereof to actuate said device to open the switch blade at a predetermined 25 time.

A further object of the invention is to provide an alarm mechanism, the alarm key of which is designed to move intermittently, for instance to move a portion of its revolution, 30 sufficient to open the switch, then stop by reason of contacting with a device connected to the switch blade, and then when the hour and minute hands of the clock again reach the hour on which the switch blade is open, 35 the alarm key will further rotate back to its original position, for again actuating the device connected to the switch blade.

In practical fields the details of construction may necessitate alterations falling within 40 the scope of what is claimed.

The invention comprises further features and combination of parts as hereinafter set forth shown in the drawings and claimed.

In the drawings:

45 Figure 1 is a view in elevation of an alarm clock mechanism, mounted in a casing in which a knife blade switch is also mounted and arranged in a lighting circuit.

Fig. 2 is a view in rear elevation of Fig. 1.

50 Fig. 3 is a sectional view on line 3—3 of Fig. 2.

Fig. 4 is an edge view of the casing for the alarm clock casing.

Referring more especially to the drawings 55 1 designates a conventional form of alarm

clock, the casing of which is mounted in a rectangular frame or casing 2 and secured by screws 3 and is provided with an alarm key 4. A circular disk 5 having an annular flange 6 is carried on the shaft 7 of the alarm 60 key 4. The inner face of the flange 6 of the disk 5 is provided with a camming projection 8. A conventional form of mechanism (not shown) is designed to be carried in the clock casing and operated by the clock mechanism, whereby the disk 5 and the shaft on which it is mounted may be actuated or rotated intermittently. For example by this mechanism, the disk is designed to rotate, so that the projection 8 will move from the 70 position at *a* to *b* and then stop until the time at which it stops, advances, and when the clock hands again reach this particular time, the disk 5 will again rotate until the projection 8 reaches the position at *a*. Secured by screws 9 to the top wall of the casing 2 is an insulating base plate 10. Secured to the plate 10 is a pair of spaced switch blade terminals 11, between which the switch blade 12 is pivotally mounted as at 13. The 80 terminals 11 are provided with a base lug 14 having a binding post 15 and a binding nut 16. Spaced terminals 17 are arranged at the other end of the plate 10, there being a lug 18 (which is secured to the plate 10 in any 85 suitable manner) having a binding post 19 for the binding nut 20. A wire or lead 21 is connected to the binding post 19 by the nut 20, and in turn to an electric light or bulb 22. A lead 23 connects the bulb and a battery 24 90 from which a wire or lead 25 extends, which in turn is connected to the binding post 15 by the nut 16. The wires or leads pass through suitable insulation bushings 26 of the casing 2. The casing 2 has an abutment 95 lug 27 to limit the switch blade to its open position. A lever 28 is pivoted at 29 to the switch blade and depends downwardly and terminates in a curved end portion 30, which overlies the flange 6 of the disk 5. A curved portion 30 has a laterally extending lug 31 engaging the inner surface of the flange 6, consequently in the path of the projection 8. A spring 32 is provided and has one end connected at 33 to the rear face of the clock case and its other end connected at 34 to the lever or depending member 28, to hold the lug 31 against the inner face of the flange 6. The circuit may contain as many bulbs or electric lights as desired, there having been 110

only one shown for illustrative purposes. These electric lights or bulbs are designed for lighting show windows of stores and the like. Heretofore, the policemen on the beat 5 or a special watchman paid by the stores go by and turn off the electric lights, say for instance around ten o'clock at night. With this improved device the clock is set, so that the shaft 7 will start to rotate at 10 o'clock 10 until the projection 8 moves from *a* to *b*. The projection 8 in moving this distance will contact with the lug 31, hence pulling the lever 28 downwardly, which will in turn open the switch blade, and the blade by contacting with the lug 27 will stop in the dotted line position. When the switch blade 12 is so stopped the disk 5 will be held at rest long enough to permit the minute hand to move enough to permit the alarm to cease, 15 and the projection 8 and the lug 31 will be on a tension, one almost in the act of passing the other. This operation will occur substantially sharp at the stroke of nine at night. The lights of the show window are 20 consequently turned out. The next day at a substantial time after ten o'clock in the day, the stopping device may again be set, and the switch closed, whereby at the proper time in the evening of the next day for instance at ten o'clock, the switch blade may 25 30

again open, as before set forth, and the lights turned out.

The invention having been set forth what is claimed as new and useful is:—

The combination with an electric circuit, 35 of a switch member in said circuit normally closed, a stationary limiting abutment for said member, a switch actuating device, pivotally suspended from the member and being spring tensioned, a predetermined actuated shaft, a disk fixed on the shaft and having an annular flange on its marginal edge, the inner circumference of said flange having a projection provided with an abrupt shoulder, the lower end of the switch actuating device being curved and overlying the marginal edge of the flange of the disk, said curved end having a lateral lug engaging the inner surface of the flange in the path of said projection, whereby, upon revoluble 40 movement of the shaft at a predetermined time, said projections will contact with the lug and open the switch member.

In testimony whereof I have signed my name to this specification in the presence of 45 two subscribing witnesses.

SAMUEL E. WRIGHT.
